DRYING APPARATUS

James H. A. Stanley McMordie, Arlington, and Manson E. Wood, Wakefield, Mass., assignors to Dewey and Almy Chemical Company, North Cambridge, Mass., a corporation of Massachusetts

Application August 2, 1940, Serial No. 349,594

15 Claims. (Cl. 34—159)

The present invention is directed particularly, although not exclusively, to apparatus of the general type described in the patent to Edward L. Moreland, Ralph D. Booth and Charles H. Danforth, No. 2,057,903, dated October 20, 1936. In that patent an apparatus is described which is operative for use in conjunction with rotary printing machines for textiles or other goods. The apparatus includes an endless backing blanket for the goods to be printed which is fed continuously over the surface of a roll of the printing machine to serve as a backing for the goods while being printed and for removing excess color. After leaving the printing machine the blanket passes through washing apparatus to remove color. The blanket then passes through drying apparatus before returning to the printing machine.

It is an object of the present invention to provide an improved drying apparatus, and more especially, a drying apparatus for a blanket used in rotary printing of textile or other goods.

Another object of the invention is the provision of improved means for guiding and feeding a driven endless blanket.

A further object of the invention is the provision of means for facilitating the removal and replacement of an endless blanket in an apparatus of the general character described in the above mentioned patent.

These and other objects of the invention will be more clearly understood from the following description in conjunction with the accompanying drawings, in which,

Fig. 1 is a diagrammatic view of a rotary textile printing assembly embodying the invention;

Fig. 2 is a fragmentary elevational view of one end of the drying unit, partly in section;

Fig. 3 is a fragmentary elevational view of the other end of the drying unit;

Fig. 4 is a sectional view taken upon the line 4—4 of Fig. 2;

Fig. 5 is an enlarged sectional view taken upon the line 5—5 of Fig. 2;

Fig. 6 is an enlarged sectional elevational view of the portion of the apparatus shown in Fig. 3;

Fig. 7 is a fragmentary perspective view of one of the parts of the drying unit;

Fig. 8 is a detail sectional elevational view of a portion of the apparatus shown in Fig. 6; and

Fig. 9 is an enlarged detail view of a portion of the apparatus shown in Fig. 2.

Before explaining in detail the present invention it is to be understood that the invention is not limited in its application to the details of

construction and arrangement of parts illustrated in the accompanying drawings, since the invention is capable of other embodiments and of being practiced or carried out in various ways. 5 Also it is to be understood that the phraseology or terminology employed herein is for the purpose of description and not of limitation, and it is not intended to limit the invention claimed herein beyond the requirements of the prior art.

The invention is illustrated in the accompanying drawings as applied to an assembly for the rotary printing of textile or other goods which comprises a rotary printing machine 10 (Fig. 1), a wetting device 11, a drying unit D carried by a suitable frame structure 12 and a washing and wringing unit 13. An endless washable blanket B is trained around a roll 14 carried by a shaft 15 mounted for rotation in the frame of the printing machine 10 and is trained over rolls 16, 17, 18, 19, 20 and 21 to a roll 22 carried upon a shaft which is mounted for rotation in the washing and wringing unit 13. The blanket B then passes over a roll 23 and through the drying unit D from which it passes over the rolls 24, 25, 26, 27, 28 and 29 to the roll 14. Power is supplied in any conventional manner to rolls 14 and 22 to move the blanket B. Roll 22 is preferably driven by any conventional slip-drive or synchronized drive so as to maintain tension on the blanket B as it enters the washing unit 13.

A roll of textile or other goods T is mounted upon a rotatable carrier 30. The web of textile material T is trained around rolls 31, 32, 33 and 34 and is passed around the roll 14 of the printing machine simultaneously with the blanket B and is then led away from the printing machine for further treatment.

The drying unit D is substantially U-shaped and comprises parallel chambers 40 and 41 positioned one above the other and connected by a chamber 42 (Figs. 4, 5 and 6). The chamber 40 is supported by spaced parallel Z-irons 43 and 44 which are secured to spaced parallel upright portions 39 of the main frame 12 (Fig. 6). The chamber 41 likewise is supported by spaced parallel Z-irons 45 and 46 which are secured to the uprights 39 of the main frame 12. The bottom of the chamber 40 and the top of the chamber 41 are closed by a plurality of panels 47 and 48 respectively which are held in place by T-irons 50 which overlap the edges of adjacent panels and are secured by bolts 51 to spaced angle irons 52 extending transversely across the chambers 40 and 41. The T-irons 50 are secured at their ends to their respective pairs of Z-bars

43, 44, 45 and 46. The sides of the chambers 40 and 41 are closed by longitudinal beams 55 which are secured to the respective Z-bars 43, 44, 45 and 46 by bolts 57. The top of the chamber 40 and the bottom of the chamber 41 are closed by panels 60 and 61 respectively. The panels 60 are formed with longitudinally extending depressions 58 upon their inner surfaces which are aligned when the panels are in their operative positions to provide low pressure air pockets for a purpose described hereinafter.

The adjacent edges of the panels 60 rest upon the aligned portions of T-bars 62 which extend transversely across the top of the chamber 40 (Figs. 4 and 5), the opposite ends of the bars 62 are detachably secured to the Z-bars 43 and 44 by bolts 63 and clamping nuts 65. The bolts 63 are pivotally secured near the ends of the T-bars 62 and engage slots 64 in the Z-bars. Likewise, the adjacent edges of the panels 61 engage the aligned portions of T-bars 66, which extend transversely across the bottom of the chamber 41 and are secured to the Z-bars 45 and 46 by bolts 67 pivotally secured to the ends of the T-bars 66 and engage slots 68 in the Z-bars 45 and 46. The T-bars 66 are tightened in place by clamping nuts 69 (Figs. 5 and 6). The adjacent edges of the panels 60 and 61 are forced against the aligned portions of the T-bars 62 and 66 respectively by adjustable and detachable power devices or jacks 70. Each jack comprises oppositely threaded screw shafts 71 and 72, which engage a nut 73. U-shaped heads 73 and 73' are fixed to the shafts 71 and 72, respectively. The heads 73 and 73' straddle the T-bars 62 and 66 respectively and engage angle irons 75 which are fixed upon the adjacent edges of the panels 60 and 61. Preferably, gaskets 78 are interposed between the aligned portions of the T-bars 62 and 66 and the adjacent edges of the panels 60 and 61.

The ends of the chambers 40 and 41 through which the blanket enters and leaves respectively are closed on one side of the blanket B by angle irons 98 which are secured to spaced upright portions 200 of the main frame 12. A felt strip 201 is cemented to a metal strip 202 which is adjustably mounted upon each of the angle irons 98 by bolts 203 engaging the angle irons 98 and passing through slots 204 in the strips 202 so that the edges of the felt strips may be brought in desired relation to the surfaces of the blanket B. The ends of the chambers 40 and 41 through which the blanket enters and leaves are closed on the other side of the blanket by a strip of felt 210 cemented to an angle iron 205. The ends of the angle irons 205 are secured to brackets 206 which are adjustably mounted upon plates 207 by screws 208 passing through slots 209 in the brackets 206 and engaging the plates 207. The plates 207 are secured to the Z-bars 43, 44, 45 and 46.

The outer wall of the chamber 42 comprises channels 80 and 81 (Fig. 6), which form an extension of the outer walls of the chambers 40 and 41, and extend between and are secured to the spaced parallel upright portions 39 of the main frame 12. A plate 82 extends between the uprights 39 and the channels 80 and 81 and is secured thereto. The inner wall of the chamber 42 is closed by the mounting M for the roll 83. The roll 83 serves to convey the blanket B from the chamber 40 through the chamber 42 and into the chamber 41.

The roll 83 is fixed upon a shaft which is

5 mounted for rotation in bearings 85 carried by the parallel portions 86 of a U-shaped plate 84 (Figs. 3 and 6). The portion 87 of the plate 84 forms the inner wall of the chamber 42. The plate 84 is provided at each end with a handle 88 which may be gripped to move the roll 83 from its operative position as shown at the right in Figs. 1 and 6 to the dotted line position shown in Fig. 2 for the purpose of facilitating the removal and replacement of the blanket B. For this purpose, a pair of rolls 90 are mounted near the bottom of each of the plate portions 86 so as to engage tracks 91 fixed upon the Z-bars 43 and 44 (Figs. 4 and 5). Rolls 92 are mounted 10 near the top of the plate portions 86 so as to engage the Z-bars 45 and 46. An angle plate 93 (Fig. 6) is fixed upon each of the plate portions 86 near its outer edges and is secured by bolts 95 to an angle plate 96 fixed to the upright frame members 39. The plates 93 and 96 are provided with centering openings 89 which may be brought into alignment by a dowel pin 97 for the purpose of assuring that the roll 83 is properly positioned in its operative location.

25 Warm air is conveyed from a heater H (Fig. 1) through an inlet passage 100 (Figs. 1 and 4) connecting with the chamber 41. After passing through the chambers 41, 42 and 40 the air is returned to the heater through a passage 101. 30 Each of the chambers 40 and 41 is provided with means for producing turbulence of the air and assure that the warm air is brought in intimate contact with the blanket B. Thus, rods 102 and 103 (Figs. 6 and 7) are secured at their opposite ends to spaced parallel angle plates 104 which are supported upon the beams 55 at opposite sides of the chambers 40 and 41. The adjacent rods 102 and 103 are twisted in opposite directions and are assembled, preferably, in units of five rods. 35 The rods of each unit are spaced longitudinally of the chambers 40 and 41 and are spaced vertically different distances from the blanket B and lie in five parallel planes which divide the space between the blanket and the opposite walls of the chambers into six substantially equal portions. Semi-cylindrical rods 36 are carried by brackets 8 which are secured to the T-bars 50, the rods 36 being arranged in the chambers 40 and 41 closer to the blanket B than the rods 40 102 and 103 to assure that the blanket does not contact with the rods 102 and 103.

45 The idler roll 25 and slack take-up roll 26 are positioned between the rolls 24 and 27 so as to provide a slack take-up loop L in the blanket B. 50 The roll 25 is mounted in bearings upon spaced parallel upright portions 105 (Fig. 2) of the main frame 12. The roll 26 is fixed upon a shaft 106 mounted for rotation in spaced bearings 107 which are slidably movable upon spaced guide rails 108 fixed upon spacing plates 109 carried by the Z-bars 45 and 46. The outer edge of each 55 of the guide rails 108 is provided with graduations G for a purpose described hereinafter. A pair of resilient tension devices 111, one connected to each of the bearings 107, tends to move the bearings to take up slack in the loop L. A safety stop 110 is provided to limit movement of the bearings 107 in the opposite direction in case of accident, such as breakage of the tension devices 111.

60 A shaft 112 (Figs. 2, 5 and 9) is mounted for rotation in bearings carried by spaced plates 113 which are secured to and extend upwardly from the Z-bars 45 and 46. Each of the plates 65 113 is reinforced by an angle iron 114. A drum

115 is fixed upon the shaft 112 just outside of each plate 113. A ratchet wheel 116 is fixed upon the shaft 112 just inside of each of the plates 113 and each cooperates with pawl 117 which is fixed upon a shaft 6 which is mounted for rotation in the plates 113. A collar 118 is fixed upon the shaft 112 near one end thereof and is provided with a radial hole 119 adapted to receive a rod 37 (Fig. 9) by which the shaft may be turned. Each drum 115 is directly connected to one of the spaced bearings 107 by one of the tensioning devices 111. Each tensioning device comprises a cable 120 connected at one end to the drum 115 and at its other end to a bolt 121 which extends across and is secured to the open ends of a U-shaped member 122. A U-shaped member 123 is slidably fitted in the member 122 so as to provide a chamber in which a coil spring 124 is housed. A turn buckle 125 connects the open ends of each one of the U-shaped members 123 with one of the movable bearings 107.

Before the apparatus is set in operation, the tension devices 111 are adjusted by turning the shaft 112 until all slack in the loop L is taken up and the desired tension is placed upon the blanket B. If necessary, one or both of the turn buckles 125 may be adjusted to bring the bearings 107 opposite corresponding graduations G on the rails 108 thereby assuring that the axis of the roll 26 is perpendicular to the direction of movement of the blanket B. Power is then supplied through the chain C to rotate the drum 14 of the printing machine. This causes the endless blanket B to move progressively through the printing machine 10, the wetting device 11, the washing and wringing device 13, and the drying unit D. At the same time, hot air from the heater H is forced through the passage 100 into the chamber 41 and thence through the chambers 42 and 40 and then is returned through the passage 101 to the heater H. As the air passes through the chambers 40 and 41 in a direction opposite to the movement of the blanket, it comes in contact successively with the adjacent rods 102 and 103 which are twisted in opposite directions and cause turbulence with minimum air resistance by deflecting the air to the right and to the left as well as toward and away from the blanket thereby ensuring efficient drying of the blanket. Inasmuch as the pressure of the air stream flowing through the drying unit is less at the outlet than at the inlet, and since the depressions 58 in the panels 61 connect directly with the outlet passage 101, the pressure upon the side of the blanket B adjacent the depressions 58 is less than that upon the other side of the blanket. This difference in pressure tends to maintain the blanket out of engagement with the twisted rods 102 and 103.

As the machine is started in operation, the springs 124 of the tension devices 111 yield to permit the bearings 107, which support the roll 26, to move toward the stop 110. Thus, the tension devices act as shock absorbers relieving the initial strain upon the blanket due to starting. After the blanket B has reached a uniform speed of movement, the tension devices 111 tends to move the bearings 107 away from the stop 110 and maintain a uniform desired tension upon the blanket B.

It occasionally is necessary to remove the blanket B from the apparatus for repair or replacement. In apparatus of this general type prior to the present invention, the removal and replacement of the blanket has been a difficult and time consuming operation. In accordance

with the present invention the time required for performing this operation is greatly reduced by the provision of means for moving the roll 83 from its operative position as shown in Fig. 6 to inoperative position as shown in dotted lines in Fig. 2. If it is desired to remove the blanket, the jacks 70 are released and removed so as to permit the panels 60 and 61 to be removed. The T-bars 62 and 66 then are removed by loosening the clamping nuts 69 and then pivoting the bolts 67 to remove the latter from the slots 68. The bolts 95 then are removed and the operators may grip the handles 88 and move the mounting 84 for the roll 83 along the rails 91 to bring the roll 83 to the position shown in dotted lines in Fig. 2. When in this position the roll 83 may be readily removed from the apparatus and thus facilitate the removal of the blanket.

When it is desired to replace the blanket the blanket is trained over the rolls 22 and 14 as well as the rolls 17, 18, 19, 20, 21, 25, 26, 27, 28 and 29. The roll 83 together with its mounting 84 is placed upon the rails 91 with the blanket between the same and the drying unit. The mounting 84 is then moved from the dotted line position shown in Fig. 2 to substantially the operative position shown in Fig. 6, thus positioning portions of the blanket B within the chambers 40 and 41. The mounting 84 is centered accurately by inserting the dowel pin 97 in the openings 93 in the plates 93 and 96. The plate 93 then is secured to the plate 96 by the bolts 95. The T-bars 62 and 66 are then replaced and secured in position by bolts 67 and clamping nuts 69. The panels 60 and 61 then are successively placed in position and forced against the aligned portions of the T-bars 62 and 66 by inserting and adjusting the jacks 70.

While the invention has been described and illustrated as applied to apparatus for removing liquid from an endless washable blanket, it will be understood that the invention is applicable broadly to heat interchange apparatus of various types, such as for drying, heating or cooling a material.

We claim:

1. In a heat interchange apparatus, a chamber, means for guiding a material through the chamber, a plurality of twisted rods extending across the chamber perpendicular to the direction of movement of said material and spaced from said material, and means for causing a gas to flow through the chamber past said rods and in contact with said material.

2. In a heat interchange apparatus, a chamber, means for guiding a material through the chamber, a plurality of twisted rods extending across the chamber perpendicular to the direction of movement of said material and spaced from said material, the adjacent rods being twisted in opposite directions, and means for causing a gas flow through the chamber past said rods and in contact with said material.

3. In a heat interchange apparatus, a chamber, means for guiding a material through the chamber, a plurality of twisted rods extending across the chamber perpendicular to the direction of movement of said material, said rods being arranged in units each containing a plurality of rods, the rods of each unit being spaced longitudinally of the chamber and arranged in the space between said material and the wall of the chamber opposite thereto so as to lie in planes dividing said space into substantially equal portions, the adjacent rods being twisted in opposite

directions, and means for causing a gas to flow through the chamber past said rods and in contact with said material.

4. In an apparatus for removing liquid from a material, a drying chamber, means for guiding the material through the chamber, a plurality of twisted rods extending across the chamber perpendicular to the direction of movement of said material, and means for causing a gas to flow through the chamber past said rods and in contact with said material, said rods being spaced from said material different distances.

5. Apparatus for drying a travelling web including a chamber through which the web passes, means for guiding the web through the chamber, a plurality of twisted rods extending across the chamber perpendicular to the direction of movement of the web and spaced from the latter, and means for causing a gas to flow through the chamber past said rods and in contact with the web, said rods being spaced from said web different distances.

6. Apparatus for drying a travelling blanket comprising a chamber through which the blanket passes, means for moving the blanket through the chamber, a plurality of twisted rods extending across the chamber perpendicular to the direction of movement of the blanket, means for maintaining the blanket out of contact with said rods, and means for causing a gas to flow through the chamber past said rods and in contact with said blanket.

7. Apparatus for drying a travelling endless blanket including a chamber through which the blanket passes, means for moving the blanket through the chamber, a plurality of twisted rods extending across the chamber perpendicular to the direction of movement of the blanket, means for maintaining the blanket out of contact with said rods, the adjacent rods being twisted in opposite directions and spaced from said blanket different distances, and means for causing a gas to flow through the chamber past said rods and in contact with said blanket.

8. Apparatus for drying a moving blanket comprising a pair of chambers one positioned over the other, removable means for closing the adjacent opposite portions of said chambers, means for circulating a drying gas through the chambers in contact with the blanket supported therein, guiding means including a roll for guiding the blanket out of one of said chambers and into the other, means for detachably securing said roll in its operative position, near one end of said chambers, and a trackway extending longitudinally of and between the chambers to guide said roll from one end of the chambers to the opposite end thereof whereby a blanket may be threaded through the apparatus.

9. Apparatus for drying a moving blanket comprising a pair of chambers one positioned over the other, detachable panels for closing each of the adjacent opposite portions of said chambers, means for guiding a blanket through said chambers in series, means for circulating a drying gas through the chambers in contact with the blanket therein, and a plurality of adjustable and detachable pressure means extending between said opposite portions and each overlapping at each end the edges of a pair of said detachable panels.

10. Apparatus for drying a travelling blanket comprising a pair of chambers one positioned over the other, detachable panels for closing each of the adjacent opposite portions of said chambers, means for guiding a blanket through said chambers in series, means for circulating a drying gas through the chambers in contact with the blanket therein, detachable cross members extending across each of said opposite portions and overlapping the adjacent edges of said panels, and a plurality of adjustable and detachable pressure means extending between said opposite portions and operative to force said panels toward said cross members.

11. Apparatus for drying a moving blanket comprising a pair of chambers one positioned over the other, detachable panels for closing each of the adjacent opposite portions of said chambers, means for circulating a drying gas through the chambers in contact with the blanket supported therein, a plurality of adjustable and detachable pressure means extending between said opposite portions and each overlapping at each end the edges of a pair of said detachable panels, guiding means including a roll for guiding the blanket out of one of said chambers and into the other, means for detachably securing said roll in its operative position near one end of said chamber, and a trackway extending longitudinally of and between the chambers to guide said roll from one end of the chambers to the opposite end thereof whereby a blanket may be threaded through the apparatus.

12. Apparatus for drying a moving blanket comprising a pair of drying chambers one positioned over the other, detachable panels for closing each of the adjacent opposite portions of said chambers, means for circulating a drying gas through the chambers in contact with the blanket supported therein, detachable cross members extending across each of said opposite portions and overlapping the adjacent edges of said panels, a plurality of adjustable and detachable pressure means extending between said opposite portions and operative to force said panels toward said cross members, guiding means including a roll for guiding the blanket out of one of said chambers and into the other, means for detachably securing said roll in its operative position near one end of said chambers, and a trackway extending longitudinally of and between the chambers to guide said roll from one end of the chambers to the opposite end thereof whereby a blanket may be threaded through the apparatus.

13. Apparatus for drying a travelling blanket including a chamber through which the blanket passes, a plurality of twisted rods extending across the chamber perpendicular to the direction of movement of the blanket, means for maintaining the blanket out of contact with said rods, and means for causing a gas to move through the chamber past said rods and in contact with said blanket, means for guiding the blanket longitudinally through the apparatus including a slack take-up roll, movable bearings for rotatably supporting said roll, and resilient means acting upon said bearings to move the same to take up slack in said blanket.

14. Apparatus for drying a travelling web comprising a pair of chambers one positioned over the other, a plurality of twisted rods extending across the chambers perpendicular to the direction of movement of the web, removable means for closing the adjacent opposite portions of said chambers, means for maintaining the web out of contact with said rods, and means for causing a gas to move through the chamber past said rods and in contact with said web, means for guiding the web longitudinally through the apparatus in-

75

cluding a slack take-up roll, movable bearings for rotatably supporting said roll, resilient means acting upon said bearings to move the same to take up slack in said web, said guide means also including a guide roll for guiding the web out of one of said chambers and into the other, means for detachably securing said guide roll in its operative position near one end of said chambers, and means for guiding said guide roll from its operative position to a position adjacent the other end of said chambers.

15. Apparatus for drying a moving web comprising a pair of chambers one positioned over the other, means for admitting and discharging a

5 drying gas into and from said chambers, removable means for closing the adjacent opposite portions of said chambers, web guiding means including a roll adjacent one end of the chambers for guiding the web out of one of said chambers and into the other, means for detachably securing the roll in its operative position, and means for supporting and guiding said roll for movement between said chambers from its operative position into a position adjacent the other end of the chambers, whereby the web may be easily threaded through said chambers.

JAMES H. A. STANLEY McMORDIE.

MANSON E. WOOD.
